UNITED STATES PATENT OFFICE.

CARLYLE B. CAMPBELL, OF SULLY, IOWA.

TUNING TRANSFORMER.

1,276,618.

Specification of Letters Patent. Patented Aug. 20, 1918.

Application filed February 16, 1917. Serial No. 149,034.

To all whom it may concern:

Be it known that I, CARLYLE B. CAMPBELL, a citizen of the United States, residing at Sully, in the county of Jasper and State of Iowa, have invented certain new and useful Improvements in Tuning Transformers; and I do hereby declare the following to be a full, clear, and exact description of the invention, such as will enable others skilled in the art to which it appertains to make and use the same.

This invention relates to new and useful improvements in tuning transformers, and the principal object of the invention is to provide a transformer in which unused portions of the inductance are completely cut off from the circuit, thereby eliminating undesired effects on wave lengths.

Another object of the invention is to provide a transformer which is divided into sections the terminals of which are connected to switches which connect and disconnect the windings as may be required.

A still further object of the invention is to provide a device having in its primary circuit a series of separate coils, the terminals of which are connected to annular contacts and contact fingers which fingers are normally bent to engage the contact to throw the coils in series and also to provide a means for separating the fingers from the contact in order to cut out certain of the coils when desired.

Still another object of the invention is to provide a novel construction of contact and contact fingers which is designed to coöperate with the switch arm and disk carried thereby.

A still further object of the invention relates in the provision of a plurality of separate coils the terminals of which are connected with the contacts and spring contacts as previously described for the primary, which are adapted to be separated by an insulating disk in order to cut out certain of the coils when so desired.

A further object of the invention is to provide a device having a suitable elevator by which the insulating disk when turned may be moved so as to free certain of the contact fingers and allow the same to move into engagement with the contact.

With these and other objects in view, the

invention consists in the novel combination and arrangement of parts which will be fully set forth in the following specification and accompanying drawings, in which:

Figure 1 is a side view in elevation of a tuning coil constructed in accordance with this invention;

60

Fig. 2 is an end view of the device;

Fig. 3 is an end view from the opposite end;

Fig. 4 is a view showing the winding diagram of the primary of the tuning coil;

65

Fig. 5 is a view showing the winding diagram of the secondary of the coil;

Fig. 6 is a detail plan view of the switch for controlling the primary winding of the tuning coil;

70

Fig. 7 is a view similar to Fig. 6 of the switch used in connection with the secondary winding of the device;

Fig. 8 is an enlarged detail fragmentary sectional view of one of the switches showing the contact and contact fingers in detail;

75

Fig. 9 is a fragmentary sectional view of the base showing the elevator secured thereto;

Fig. 10 is an enlarged fragmentary detail end view of Fig. 8;

80

Fig. 11 is a plan view of a modified form of the switch showing the same when the disk is eliminated;

Fig. 12 is an enlarged fragmentary detail sectional view of the base similar to Fig. 8, showing the contact attached thereto and illustrating in detail the modified form of contact fingers;

85

Fig. 13 is an end view of Fig. 12;

90

Fig. 14 is a detail edge view partly in section showing the switch blade; and

Fig. 15 is a sectional view on line 15—15 of Fig. 14 showing the same on an enlarged scale for clearly illustrating the detailed construction.

Referring to the drawings, the numeral 1 designates the base of the device supporting thereon the primary designated by the numeral 2. This primary consists of the usual hollow spool wound with the usual primary winding designated generically by the numeral 3 which primary winding consists of a plurality of coils of wire 3^a the terminals of which are independently connected to the contact element which will be more fully

100

105

hereinafter described. Secured within and extending longitudinally through the primary 2 and projecting well beyond one end of said primary are the guide bars 4, the 5 ends of which opposite those supported in the primary are secured within a pedestal 5 mounted adjacent the end of the base opposite that on which the primary is mounted. The rods 4 form supports for the secondary 10 designated generically by the numeral 6 which comprises a spool 7 having the secondary coil designated generically by the numeral 8 wound thereon which secondary coil consists of a plurality of independent 15 coils 8^a which are connected to the secondary switch which will be more fully hereinafter described. In the type of primary switch illustrated in Fig. 6 it will be seen that the same consists of a plurality of contacts 9 ar- 20 ranged in annular series and attached to a stationary base 10 by means of suitable pins 11, which extend through said base and are provided with nuts 12 on their inner ends. Extending over and normally tend- 25 ing to engage the upper ends of the contact 9 are the contact fingers 13 which are formed on the eight portions 14 of a plate 15 which is attached to the base by means of a bolt 16 having a nut 17 threaded thereon which 30 plate is provided with a spur 18 for engaging in the face of the plate 10 in order to hold the spring finger against rotary movement on the base plate.

As previously described the finger 13 nor- 35 mally tends to engage the contact 9 so as to connect the terminal of the coil which is connected to said spring finger with the terminal of the next adjacent coil which is connected to the contact.

40 As illustrated in Fig. 10, the side edges of each spring finger 13 are upturned as at 19 while the upper corners of the contact 9 are beveled as at 20 to allow for the entrance of the rotatably mounted contact arm which 45 will be more fully hereinafter described between the contacts and spring fingers. Secured to the base 10 centrally of the annular series of contacts 9 is a pivot stud 21 having rotatably mounted thereon an insulating 50 disk 22 which is relatively thin and provided with a radial slot 23 which forms a break in the circumferential portion of the disk. A stop lug 23 is formed on the disk and extends outwardly from its periphery 55 adjacent one side of the slot and is adapted to engage a stop pin 24 secured to the base in order to limit the rotary movement of the disk.

Attached to the underside of the disk and 60 in electrical contact with the stud 21 is a contact arm 25 which is adapted to engage the upper ends of the contacts 9 successively as the disk is rotated, until the same moves into engagement with the last contact at 65 which time the stop lug 23 will engage the

stop pin 24 and thereby prevent further movement of the disk in that direction. In order to prevent the edge 23^a of the disk 22 from separating the contact springs 13 from the contacts 9 after the edge 23^b of said disk 70 has been moved so as to free said contact fingers a suitable elevator designated by the numeral 26 is provided and consists of an arcuate plate having its upper side inclined as at 27 which plate is attached to the base 75 10 between the first and last contacts 9 by means of suitable threaded studs 28 having the nuts 29 threaded thereon.

In order to prevent the disk from being turned in a reverse direction after the same 80 has reached its rearmost limit of movement the edge 23^b of the slot 23 will engage the end edge of the plate 26 as will be clearly seen upon reference to Figs. 6 and 9. It will be evident that when it is desired to connect 85 certain of the coils together and throw the same in circuit with the remaining coils, the disk 22 is rotated in a clockwise direction thereby moving the contact arm 25 over the contacts 9 until the contact arm rests on the 90 desired contact.

It will thus be seen that the contacts and spring fingers beyond the point where the contact 25 engages its respective contact 9 will be held separated thereby disconnecting 95 their respective coils. While owing to the fact that the edge 23^a of the slot 23 in the disk 22 rests on the inclined base 27 of the plate 26 when the contact 25 is in starting position, it will be seen that the incline 27 100 will guide the edge 23^a upwardly and over the top of the spring fingers 13 lying between the contact arm 25 and the elevator thereby allowing said fingers to engage their 105 respective contacts to throw into the circuit a desired number of coils. In this way it will be seen that the effect of the loose ends of the primary winding on the apparatus, will be eliminated as these coils are completely cut out of the circuit. 110

In the secondary switch illustrated in Fig. 7, the contacts are designated by the numeral 9^a while the contact spring fingers are designated by the numeral 13^a. These fingers normally tend to move into engagement 115 with the contacts 9^a in order to cut in their respective coils, but owing to the fact that the contacts are arranged only in a semi-circular series it will be seen that only a semi-circular insulating plate 30 is required. 120 This plate is rotatably mounted on the central stud 31 which is in electrical communication with the contact arm 32 secured to the underside of the plate adjacent one of its radial edges which contact arm engages the 125 contacts 9^a. In this construction it will be seen that the use of the elevator is eliminated as the plate only makes a part of a revolution and it will be seen that as the contact arm 32 is moved in a counter-clockwise di- 130

rection from the position illustrated in Fig. 7, the coils will gradually be cut out and will remain out of circuit owing to the fact that the plate 30 separates the spring fingers 5 from the contacts.

In the modified form of primary switch illustrated in Fig. 11, it will be seen that the contacts are designated by the numeral 33 and are arranged in annular series as in 10 the primary switch in Fig. 6. The contact arm designated by the numeral 34 is pivoted centrally of the annular series of contacts 33 and is arranged so that its ends project over said contacts as clearly illustrated 15 in Fig. 11. A suitable insulating plate 35 is riveted or otherwise attached to the upper side of said arm adjacent the end which bears on the contact 33 and both the contact arm 34 and the insulating plate are beveled as at 36 in order to facilitate their 20 entrance between the contacts and the spring fingers which will be more fully hereinafter described.

The spring fingers above referred to are 25 best illustrated in Fig. 12 and are designated by the numeral 37 and these fingers like those previously described are formed integrally with a plate 38 having a spur 39 which enters the base plate to which the contacts 33 are secured, and which plate is held 30 in place by a suitable bolt 40. The ends of the spring fingers 37 are downturned as at 41 and these downturned portions are provided at their lower corners with beveled 35 faces 42 which coöperate with the beveled edges 43 of the contact 33 in admitting the contact arm 34 and the insulating plate 35.

In this construction of switch it will be seen that owing to the fact that the contact 40 plate 35 separates the spring fingers from its respective contact the coils in the rear of said switch arm will be cut in while those 45 of the forward side will be cut out of the series. It will be understood that the switch arm 34 is connected by a wire 44 to the binding post 45 while the opposite binding post 46 is connected to one terminal of the first section of the primary coil. The secondary coil is connected through its switch by connecting a wire 47 to the post 31 and to the binding post 48 thereby electrically connecting 50 the switch arm 32 with the binding post. One terminal of the first coil 8^a of the secondary winding is connected to the binding post 49 while the opposite terminal as 55 previously described is connected to the first contact 9^a of the secondary switch, while the first terminal of the second coil 8^a of the secondary winding 8 is connected to the 60 spring finger 13^a which engages the first contact 9^a. The opposite terminal of the second coil is then connected to the second contact 9^a as will be clearly shown in Fig. 5. The same wiring system is used in the primary 65 illustrated in Fig. 4, and it will thus be seen

that the primary and secondary windings are separated into a plurality of separate units having their terminals so arranged that they normally tend to contact in order to cut in the whole coil and yet capable of 70 being separated so that the units may be progressively cut in the coil and also make contact through the contact arm with the outer circuit.

In the modified form of the invention, 75 while the unused units of the coil are allowed to be in series with each other it will be seen that they are separated from the portion which is being used, thereby avoiding any possibility of the same affecting the 80 operation of the instrument.

While in the foregoing there has been shown and described the preferred embodiment of this invention, it is to be understood that such changes may be made in the combination and arrangement of parts as will fall within the spirit and scope of the appended claims.

What is claimed is:—

1. In a transformer, a plurality of independent coils of wire, contacts connected to one set of terminals of the coils, contact springs connected to the opposite terminals of the coils and arranged to engage the first mentioned contacts to normally tend to connect all of the coils in series, a switch arm adapted to engage the contacts and to separate the said contacts and contact springs to cut out that part of the coil ahead of the switch arm, and an insulating plate secured 100 to the upper side of the switch arm and extending between the contacts of the last coil in use and the contact spring of the first unused coil.

2. In a transformer, a plurality of independent coils of wire, contacts connected to one set of terminals of the coils, contact springs connected to the opposite terminals of the coils and arranged to engage the first mentioned contacts to normally tend to connect all of the coils in series, a switch arm adapted to engage the contacts and to separate the said contacts and contact springs to cut out that part of the coil ahead 110 of the switch arm, and an insulating plate secured to the upper side of the switch arm for extending between the contacts and contact springs of the unused portion of the coil to prevent the units from being connected 115 and affecting that part of the coil which is in use.

3. In a transformer, a plurality of independent coils of wire, contacts connected to one set of terminals of the coils, contact springs connected to the opposite terminals 125 of the coils and arranged to engage the first mentioned contacts to normally tend to connect all of the coils in series, a switch arm adapted to engage the contacts and to separate the said contacts and contact springs to 130

cut out that part of the coil ahead of the switch arm, and an insulating plate secured to the upper side of the switch arm for extending between the contacts and contact 5 springs of the unused portion of the coil to prevent the units from being connected and affecting that part of the coil which is in use, and an elevator for raising the plate

from operative position with relation to the contacts in the rear of the switch arm. 10

In testimony whereof I affix my signature in presence of two witnesses.

CARLYLE B. CAMPBELL.
